UNITED STATES PATENT OFFICE.

OSCAR H. PIEPER AND ALPHONSE F. PIEPER, OF ROCHESTER, NEW YORK.

PULLEY-GUARD.

1,271,612.

Specification of Letters Patent.

Patented July 9, 1918.

Original application filed May 27, 1912, Serial No. 699,938. Divided and this application filed November 12, 1917. Serial No. 201,544.

To all whom it may concern:

Be it known that we, OSCAR H. PIEPER and ALPHONSE F. PIEPER, both of Rochester, in the county of Monroe and State of New York, have invented certain new and useful Improvements in Pulley-Guards; and we do hereby declare the following to be a full, clear, and exact description of the same, reference being had to the accompanying drawings, forming a part of this specification, and to the reference-numerals marked thereon.

The invention relates to pulley guards, more particularly of the type used in connection with small pulleys such as employed on dental engines and similar machinery. The particular object lies in the provision of a simple, economical and otherwise practical arrangement of guard, coöperative with a plurality of pulleys in stepped relationship, and readily adjustable into and out of operating position. To these and other ends the invention consists in certain improvements and combinations of parts, all as will be hereinafter more fully described, the novel features being pointed out in the claims at the end of the specification.

In the drawings:

Figure 1 is an end elevation of a spindle 30 provided with a plurality of pulleys and showing the application of the improved guard in operating position;

Fig. 2 is a similar view, with the spindle and pulleys removed, and illustrating the 35 guard in its outermost or inoperative position;

Fig. 3 is a side elevation of the parts as appearing in Fig. 1, and

Fig. 4 is a similar view, with parts in 40 section, and illustrating the guard in its outermost position.

Similar reference numerals in the several figures indicate the same parts.

This application is a division of an original 45 application filed by us May 27, 1912, Serial No. 699,938. The embodiment herein illustrated comprises a rotary spindle 1, carrying a pair of stepped pulleys 2 and 3 which are fixed thereon. The spindle 1 50 rotates within a stationary bearing 4 which latter carries a collar 5, fixed to the bearing by means of a set screw 6.

The guard consists of a central portion 7 and laterally extending guard portions 55 8 and 9. The central portion 7 is in substan-

tial alinement with the collar 5, while the lateral guard portions 8 and 9 are arranged to coöperate respectively with the pulleys 3 and 2.

The guard portions 8 and 9 are preferably 60 in the form of flanges, of an integral piece of sheet metal, and the entire guard is movable toward and from the pulleys. To this end, the collar 5 is provided with oppositely arranged guide openings 10, preferably 65 extending entirely therethrough, and the guard carries a pair of pins 11 which are fixed upon the central portion 7, and are slidable in the openings 10. It is desirable to limit the outward movement of the guard, and to accomplish this, the pins 11 are cut away or recessed for a portion of their length, as indicated by 12, the length of such cut-away 70 portions determining the amount of outward movement of the guard to its inoperative 75 position. Arranged within the guide openings 10 are stops or projections 13 which extend into the recessed portions 12 and engage the ends of said recesses, as indicated in Fig. 2.

The structure described provides an exceedingly simple and practical device, and lends itself nicely to the character of adjustable guard required for fine dental apparatus.

We claim as our invention:

1. The combination with a rotatable spindle having a plurality of stepped pulleys thereon, of a bearing for the spindle, a collar fixed on the bearing, and a stepped guard coöperating with said pulleys and 90 slidable on the collar transversely of the spindle axis.

2. The combination with a rotatable spindle having a pulley thereon, of a bearing for the spindle, a collar fixed on the 95 bearing and having guide openings extending through opposite portions thereof, and a guard carrying oppositely arranged pins which are slidable in said openings.

3. The combination with a rotatable 100 spindle having a plurality of stepped pulleys thereon, of a bearing for the spindle, a collar fixed on the bearing and having guide openings extending through opposite portions thereof, and a stepped guard coöperating with said pulleys and carrying 105 oppositely arranged pins which are slidable in said openings.

4. The combination with a rotatable 110 spindle having a plurality of stepped pul-

leys thereon, of a bearing for the spindle, a collar fixed on the bearing and having guide openings extending through opposite portions thereof, a stepped guard coöperating 5 with said pulleys and carrying oppositely arranged pins which are slidable in said openings, each of the pins having recesses extending partially along one side, and limiting stops in the openings which 10 engage said recesses and limit the outward movement of the guard.

5. The combination with a rotatable spindle having a plurality of stepped pulleys thereon, of a bearing for the spindle,

a collar fixed on the bearing and having 15 guide openings extending through opposite portions thereof, a guard embodying a central outer portion carrying oppositely arranged pins which are slidable in the openings, stepped guard portions coöperating 20 with said pulleys, the aforesaid pins having recesses extending partially along one side, and limiting stops in the openings which engage said recesses and limit the outward movement of the guard.

OSCAR H. PIEPER.
ALPHONSE F. PIEPER.

Copies of this patent may be obtained for five cents each, by addressing the "Commissioner of Patents, Washington, D. C."
